STABILIZING DEVICE FOR CAR TRUCKS

Filed Sept. 28, 1936

Fig. 1.

UNITED STATES PATENT OFFICE

2,142,426

STABILIZING DEVICE FOR CAR TRUCKS

Edwin W. Webb, Chicago, Ill., assignor to Standard Car Truck Company, Chicago, Ill., a corporation of New Jersey

Application September 28, 1936, Serial No. 102,937

8 Claims. (Cl. 105—193)

This invention relates to stabilized car trucks. It is a general object of the invention to provide a novel and improved stabilized car truck wherein it is unnecessary to utilize a spring plank between the opposite side frames of the truck and wherein cumulative periodic action of the bolster springs is prevented.

Another object is to provide improvements of my invention disclosed in U. S. Letters Patent No. 1,894,386 entitled "Spring damping truck" granted in my name on January 17, 1933.

A more specific object is to provide, in a car truck incorporating stabilizing wedges interposed between the truck bolster and the bolster columns of a side frame, means to prevent uneven wear of the wedges.

Another specific object is to provide, in a stabilized truck of the general construction disclosed in my aforementioned patent, means for retaining the stabilizing wedges assembled with the bolster as the bolster is disengaged from the side frame.

The objects and advantages of the invention will more fully appear from the following description, made in connection with the accompanying drawing, wherein like reference characters refer to the same or similar parts throughout the various views, and in which,

Fig. 1 is a view partly in side elevation and partly in vertical section of a portion of a car truck embodying the invention;

Fig. 2 is a horizontal section taken substantially on the line 2—2 of Fig. 1, as indicated by the arrows, but showing parts of the bolster broken away to more clearly illustrate the construction of other parts;

Fig. 3 is a view in side elevation looking outwardly toward the inner surface of one of the outer wedges;

Fig. 4 is a vertical section taken on the line 4—4 of Fig. 3, as indicated by the arrows;

Fig. 5 is a plan view of one of the inner wedges;

Fig. 6 is a section taken on the line 6—6 of Fig. 5, as indicated by the arrows; and

Fig. 7 is a view in side elevation of the inner wedge as shown in Fig. 5.

Referring to the drawing, portions of a side frame 8 of a car truck are illustrated and this side frame is provided with the usual bolster opening 9, the sides of which are defined by bolster columns 10. The lower parts of these bolster columns 10 are spaced farther apart than the upper parts of these columns, so as to permit of ready removal of the bolster 11 which is normally received within the bolster opening 9

between the upper portions of the columns 10. The truck bolster 11 is supported near its ends by standard A. R. A. bolster springs 12 from the side frames 8, these springs resting on lower bearing plates 13 mounted on the spring seats 5 of the side frames. The outer springs 12 of the spring group are laterally spaced from the inner springs 12 a greater distance than usual for a purpose presently to appear. The bolster 11 is equipped with the usual inner and outer stop flanges 14 and 15 respectively which cooperate with the sides of the upper portions of the bolster columns 11 to prevent anything more than the most limited lateral motion of the bolster 11 relative to the side frames. 15

In accordance with the invention, heavy wear plates 16 are riveted or otherwise secured to the upper portions of the faces of the bolster columns 10. Adjacent these wear plates the sides of the bolster 11 are provided with recesses 17 20 which project inwardly from the vertical side outlines of the bolster to a web 18 disposed chiefly in a vertical plane and projecting upwardly from the bottom of the bolster to an overhanging web or flange 19 at the top of the bolster. Directly opposite the wear plates 16 the central sections of the webs 18 are provided with recessed ball contours 20 of substantially half spherical shape. The outer surfaces of the central sections of the webs 18 immediately adjacent the ball contours 20 lie in planes which are diagonally inclined upwardly and outwardly towards the sides of the bolster. 25

Received within each recess 17 of the bolster between a web 18 and the adjacent wear plate 16 are a pair of cooperating stabilizing members which comprise wedges 21 and 22 respectively. The outer wedges 21 have heavy vertical outer surfaces which bear against the wear plates 16 for sliding movement relative thereto. The 40 inwardly facing surfaces of the outer wedges 21 incline upwardly and outwardly at an acute angle to the outer surfaces of the outer wedges. The bottoms of the outer wedges 21 are provided with downwardly projecting bosses 21a 45 which are encircled by the upper ends of coiled springs 23 which bear at their lower ends on the bearing plates 13, these bearing plates being equipped with bosses 13a to receive the lower ends of the springs 23. These springs 23 are 50 located intermediate the outer and inner springs 12 of the bolster spring group and the outer and inner springs of this group are more widely spaced than usual to permit reception of the springs 23 between the same. The springs 23 55

which may be called stabilizing springs in contradistinction to the bolster springs 12 are much lighter and of materially less capacity than the bolster springs 12. The inner wedges 22 have 5 heavy inwardly projecting half spherical-shape projections forming ball surfaces 22a which are received within the ball contours 20 of the bolster. These inner wedges also have front and rear flanges 22b projecting from plane surfaced 10 faces contacting the inclined faces of the outer wedges 21 and these flanges overlie front and rear portions of the outer wedges 21 so that the outer wedges are in reality received within channels in the inner wedges.

15 The inner wedges 22 are, of course, held from lateral movement relative to the truck lengthwise of the bolster by reason of the reception of the half spherical-shape projections 22a within the ball contours 20 of the bolster. The outer 20 wedges 21 in turn are held from lateral movement relative to the truck longitudinally of the bolster by the flanges 22b of the inner wedges 22. Of course, the front and rear portions of the web 18 of the bolster will also prevent lateral 25 displacement of the wedges.

To retain the outer and inner wedges 21 and 22 respectively, in assembled position relative to the bolster 11 when the bolster is removed from the side frames, diagonally inclined slots 21b are 30 provided in the outer wedges 21 extending from front to rear of the same and across pins 24 carried by the front and rear portions of the webs 18 of the bolster extend across the recesses 17 and project through the diagonal slots 21b. These 35 slots 21b are of sufficient length to permit the necessary upward and downward sliding movement of the outer wedges 21 relative to the wear plates 16.

When the truck embodying the invention is in 40 use cumulative periodic action of the bolster springs is prevented by reason of the use of the outer and inner wedges 21 and 22 respectively and the springs 23. As the bolster 11 tends to lower relative to the side frames 8 during compressive action of the bolster springs 12, the inner 45 wedges 22 tend to slide downwardly on the outer wedges 21 but this sliding movement is resisted by the springs 23. Accordingly, the pairs of wedges 22 and 21 are brought into tighter wedging 50 relation between the wear plates 16 and the bolster and while the outer wedges 21 may slide relative to the wear plates 16, the frictional resistance offered by the wedges to this sliding movement dampens the action of the bolster springs 12 so as to break down the natural harmonic 55 action of these springs and prevent cumulative periodic action of the same as the truck passes over rail joints at a certain speed. By reason of the use of the ball sections 22a on the inner wedges and the ball contours 20 in the bolster even pressure is applied from the bolster to the inner wedges 22 at all times irrespective of the particular position of the bolster relative to the side frames. Thus if one end of the bolster 60 should move slightly ahead of the other end of the same, even pressure is applied to the wedges. There is no tendency for the wedges to wear unevenly by reason of this fact as might otherwise be the case if the universal connection 65 between the inner wedges and the bolster were not made.

While in the embodiment shown the inner wedges are equipped with the ball surfaces 22a and the bolster is provided with the ball contours 20, it will be understood that a reversal 70

of these parts is the mechanical equivalent of the structure shown.

It will, of course, be understood that various changes may be made in the form, details, arrangement and proportions of the various parts without departing from the scope of the present invention, which, generally stated, consists in the matter shown and described and set forth in the appended claims.

What is claimed is:

1. In a car truck, a side frame having a lateral bolster opening therein and having columns adjacent said bolster opening, a bolster received within said bolster opening, springs supporting said bolster from said side frame, wedges arranged in pairs between the sides of said bolster and said columns, certain wedges of each pair and said bolster having universal joint connections and springs supporting said pairs of wedges on said side frame.

2. In a car truck, a side frame having a lateral bolster opening therein and having columns adjacent said bolster opening, a bolster received within said bolster opening, springs supporting said bolster from said side frame, inner and outer wedges arranged in pairs between the sides of said bolster and said columns, the inner wedges of said pairs having partially spherical surfaces thereon contacting the bolster and said bolster having partially spherical contours therein to receive the partially spherical surfaces of said inner wedges and springs supporting said pairs of wedges on said side frame.

3. In a car truck, a side frame having a lateral bolster opening therein and having columns adjacent said bolster opening, a bolster having an end portion received within said bolster opening, bolster springs supporting said end of said bolster from said side frame, pairs of stabilizing members interposed between the sides of said bolster and said columns, one member of each pair bearing against a column and having a diagonal surface thereon for engaging the other member of the pair, the other member of the pair engaging the diagonal surface above specified and including a ball section received within a correspondingly shaped recess in the side wall of said bolster and springs supporting said stabilizing members from the side frame.

4. In a car truck, side frames having bolster openings and columns adjacent the same, a bolster structure having ends disposed within said bolster openings, bolster springs supporting the ends of said bolster structure from said side frames, pairs of oppositely disposed stabilizing members interposed between the sides of said bolster structure and said columns, the ends of said bolster structure bearing against one of each pair of said members, springs interposed between the other member of each pair and portions of said side frames, said last mentioned springs urging said stabilizing members into wedging relation between said bolster structure and said columns as said bolster springs are increasingly compressed and means retaining said stabilizing members in assembled relation on the said bolster structure as the bolster structure is removed from said bolster openings in said side frames.

5. A bolster for stabilized trucks having an end portion adapted to be received within the bolster opening of a side frame, the sides of said end portion having half spherical shaped ball contours therein to receive stabilizing members.

6. A bolster for stabilized trucks having an end portion adapted to be received within a bolster

opening in a side frame, the sides of said end portion having recesses therein within which stabilizing members may be received and the walls of said recessed portions having contours 5 of partly spherical shape.

7. In a car truck, a side frame having a lateral bolster opening therein and having columns adjacent said bolster opening, a bolster received 10 within said bolster opening, bolster springs supporting said bolster from said side frame, stabilizing wedges arranged in pairs between the sides of said bolster and said columns, certain wedges of each pair having integral rounded surfaces and said bolster having rounded contours 15 receiving said rounded surfaces and stabilizing springs of materially less capacity than said bolster springs supporting said pairs of wedges on said side frames.

springs supporting said pairs of wedges on said side frame.

8. In a car truck, a side frame having a lateral bolster opening therein and having columns adjacent said bolster opening, a bolster received 5 within said bolster opening, bolster springs supporting said bolster from said side frame, stabilizing wedges arranged in pairs between the sides of said bolster and said columns, certain wedges of each pair having integral rounded surfaces and said bolster having rounded contours 10 receiving said rounded surfaces and stabilizing springs of materially less capacity than said bolster springs supporting said pairs of wedges on said side frames.
